2,396,537

SOOT CATCHER FOR FURNACES

George Sayer, Toronto, Ontario, Canada

Application June 7, 1944, Serial No. 539,223

7 Claims. (Cl. 126—243)

My invention comprehends a tray especially adapted for catching soot and other deposits in cleaning the flues of a hot-water furnace. In order to derive maximum efficiency in the exchange of heat in the operation of a domestic furnace of this type it is generally recognized that it is highly important that the coil flues be cleared of soot at frequent intervals, which, as customarily performed, is inclined to be a messy and objectionable task. The usual practice in raking and brushing the flues is to draw accumulated soot through the clean-out opening and allow it to drop onto the floor, or, at best, to endeavour to catch such soot in a shovel or other receptacle held at the level of the opening. No matter how carefully the householder attempts to carry out this operation it usually results in spilling all or a considerable part of the soot, thus polluting the atmosphere in the vicinity of the operator and soiling both his clothing and person. Such objectionable procedure may be simply and conveniently overcome by raking or brushing the soot down the flues so as to cause it to fall into the combustion chamber where it is caught on a tray held over the fire-bed.

Essentially the invention concerns a tray for this purpose, designed to be fitted in the combustion chamber, and supported by an attachment device at a suitable elevation between the coils and the fire-bed so that it will serve to catch refuse dropped through the coil-flues in the cleaning process.

It is an object of my invention to provide a highly efficient and serviceable tray which may be used by inserting it through the fire-door opening and which may be spread in the combustion chamber to catch virtually all the refuse dropped through the coil-flues.

It is a further object to produce a tray of this character having spreadable sections which can be opened to the full width of the combustion chamber when the device is inserted through the fire-door opening.

It is a still further object to furnish the tray with means by which it may be readily suspended in applied position within the furnace.

A distinctive feature of the invention is that it is comparatively cheap to manufacture and easy to use.

The invention is illustrated in the accompanying drawing, in which:

Fig. 1 is a vertical section of the tray depicted in applied position in a furnace.

Fig. 2 is a perspective aspect of the tray showing it spread ready for use.

Fig. 3 is a plan view thereof depicting the spreadable parts of the tray body in collapsed position, the spread position being indicated in dash lines.

Fig. 4 is a perspective view of the tray showing a variant form of attachment means.

Fig. 5 is a lengthwise section thereof.

Like numerals of reference indicate corresponding parts in each of the figures throughout the drawing of the invention.

In carrying out my invention I provide a soot catcher in the form of a tray capable of being inserted through the fire-door opening of a furnace and of a length to extend to the back wall thereof. Since the vertical flue-passages of the coils are distributed around the upper region of the combustion chamber it is necessary that the tray shall cover the entire area of the fire-bed, and on account of the comparatively narrow fuel-door opening it is requisite that the tray be of a collapsible structure capable of being spread upon insertion into the combustion chamber.

Desirably I construct the tray of a main section 6 and side sections 7. The main section is a flat member having parallel sides and of a width slightly less than the fuel door opening 8 for passing freely therethrough. It is of a reach such as to project from the said opening when the front end 9 is positioned in close proximity to the back wall of the combustion chamber 10. Said front is angular and its edge portion recedes from an intermediate point so as to conform approximately to the rotundity of the combustion chamber such that the intervening gap will provide a passage for gases to ascend to the coil-flues 11. The main section is of sheet metal stiffened in any manner common to the art.

The side sections 7 are also of sheet metal. They rest upon the main section and are individually pivoted to the main section at the rear end 12 thereof, as at 13, for movement to and away from each other, for which purpose they are supplied with divergent handles 14. A lip 15 is formed at the front of the main section for engaging the distal edges of the side sections in the closed positions of these members or in order to preclude any untoward bending or straining of the components in the removal of the tray with its load after the cleaning operation has been performed.

The outer edges of the side sections 7 are of polygonal contour such as to approximate the

rotundity of the combustion chamber when they are in their spread positions as in Fig. 1. The polygonal sides thus formed leave gaps for passages of gases to pass to the coils, and these sides are supplied with shallow, upright walls 16.

The tray is preferably attached in suspended position as by the suspension device shown in Figs. 1, 2 and 3. This device comprises a rectangular frame denoted as a whole at 17, and which is of a width to fit within the frame 18 of the opening 8 and is constructed integral with or secured to the rear of the main section 6. The side pieces 19 are slotted as at 20 to fit onto the flanges 21 of said frame 18 and the top piece 22 is supplied with a hand screw 23 for tightening against said flange 21.

It will be manifest that by this construction the tray may be readily fitted in the furnace and suspended by the attachment device so that the side sections can be spread to catch soot that is caused to fall through the coil-flues in the cleaning operation, which operation is of course performed when the fire is low.

Adverting to Figs. 4 and 5, there is herein depicted a variant form of the attachment device, which comprises uprights 24 rigid with the rear of the main section for fitting inside of the fuel door opening. The uprights have outwardly directed lugs 25 for engaging the respective outer edges of the sides or flanges of the frame 18 of the opening 8. The main section has an element or elements as at 26 for seating on the bottom part 27 of the frame 18 and provided with a lug 28 for inwardly shouldering against the same. By this arrangement the tray is held in place by its own weight due to the overhang. It will be understood that the side sections are brought to a closed position in order to remove the tray from the furnace.

I claim:

1. A soot tray for a furnace provided with a fuel door opening, said soot tray comprising a main section of an elongated shape having parallel sides and being insertible endwise through the fuel door opening to extend across the furnace combustion chamber, and side sections swingably supported upon said main section for spreading within the combustion chamber, said side sections being of a segmental shape so as to form with said main section an approximately circular tray when spread.

2. A soot tray of the kind described comprising a main section of an elongated shape for insertion endwise through a fuel door opening of a furnace so as to extend across the furnace combustion chamber, side sections supported upon said main section and pivoted to the outer end

thereof for spreading within the combustion chamber, and a lip carried by the inner end of said main section for engagement with the distal ends of said side sections.

3. A soot tray of the kind described comprising a main section of an elongated shape for insertion endwise through a fuel door opening of a furnace so as to extend across the furnace combustion chamber, side sections supported upon said main section and pivoted to the outer end thereof for spreading within the combustion chamber, said side sections having outer edges of a polygonal contour, and walls formed on said outer edges and conforming to the contour thereof.

4. A soot tray as defined in claim 1, in which the side sections are pivoted at their outer ends to spread within the combustion chamber, and in which handles are provided on said side sections outwardly of their pivotal connections.

5. A soot tray as defined in claim 1, in which the side sections have inner edges which meet when the side sections are in closed position, and in which said side sections have outer edges provided with soot retaining walls terminated short of the forward ends of the said inner edges so as to provide a frontal discharge opening for emptying the tray when the side sections are in closed position.

6. A soot tray of the kind described comprising a main section of an elongated shape for insertion endwise through a fuel door opening of a furnace so as to extend across the furnace combustion chamber, side sections supported upon said main section and pivoted to the outer end thereof for spreading within the combustion chamber and a device forming an interfitting connection between the inner end of said main section and the distal ends of said side sections in the non-spread positions of the side sections.

7. A soot tray for a furnace provided with a fuel door opening surrounded by a frame, said soot tray comprising a main section of an elongated shape having substantially parallel sides and being insertible endwise through the fuel door opening to extend across the furnace combustion chamber, side sections swingably supported upon said main section for spreading within the combustion chamber, said side sections being of a segmental shape so as to form with said main section an approximately circular tray when spread, and means provided on the outer end of said main section for detachably supporting the tray on the frame of the fuel door opening whereby the main section is rigidly held so that the side sections may be spread.
